US0D1078689S

(12) **United States Design Patent** (10) Patent No.: **US D1,078,689 S**
(45) Date of Patent: ** Jun. 10, 2025

(54) **ELECTRONIC DEVICE**

(71) Applicant: **Masimo Corporation**, Irvine, CA (US)

(72) Inventor: **Sujin Hwang**, Irvine, CA (US)

(73) Assignee: **Masimo Corporation**, Irvine, CA (US)

(**) Term: **15 Years**

(21) Appl. No.: **29/868,700**

(22) Filed: **Dec. 12, 2022**

(51) LOC (15) Cl. **14-03**

(52) U.S. Cl.

USPC **D14/217**

(57) **CLAIM**

The ornamental design for an electronic device, as shown and described.

DESCRIPTION

FIG. 1 is a top perspective view of an electronic device embodying our new design;

FIG. 2 is another top perspective view thereof;

FIG. 3 is a bottom perspective view thereof;

FIG. 4 is another bottom perspective view thereof;

FIG. 5 is top view thereof;

FIG. 6 is bottom view thereof;

FIG. 7 is a front view thereof;

FIG. 8 is a rear view thereof;

FIG. 9 is a side view thereof; and,

FIG. 10 is another side view thereof.

Broken lines, where shown, are used to illustrate portions of the electronic device that form no part of the claimed design. In some embodiments, the electronic device is a wireless communication hub that can wirelessly communicate with one or more other electronic devices. The other electronic devices may be cameras and/or physiological sensors.
